UNITED STATES PATENT OFFICE.

ERWIN A. GEIGER, OF WESTFIELD, NEW JERSEY, ASSIGNEE TO RAPID ADDRESSING MACHINE COMPANY, A CORPORATION OF NEW YORK.

HAND-OPERATED ADDRESSING MACHINE.

Application filed December 27, 1926. Serial No. 157,028.

This invention embodies certain improvements on hand operated addressing machines of the type illustrated in patents to Edwin D. Belknap No. 1,208,263, granted December 12, 1916, and No. 1,473,169, granted November 6th, 1923. The best form of apparatus embodying this particular invention at present known to me is illustrated in the accompanying five sheets of drawings in which:

Fig. 1 is a side elevation of the machine.

Fig. 2 is a detail elevation of the hand crank and a portion of the duplicating mechanism in position to begin duplicate printing.

Fig. 3 is a plan view.

Fig. 4 is a fragmentary detail view of the card feed linkage in position for card feeding corresponding to that shown in Fig. 1.

Fig. 5 is a similar view showing parts in the position assumed when a card is just entering the printing zone.

Fig. 6 is a similar view showing the linkage tripped to disable the card feeding apparatus preparatory to repeat printing from the card then in the printing zone corresponding to that of the remainder of the tripping mechanism shown in Fig. 2.

Fig. 7 is a vertical cross section on line 7—7 of Fig. 1.

Fig. 8 is a similar section showing the parts in position assumed for skipping, with the clutch disengaged.

Fig. 9 is a detail of the clutch shown in Figs. 7 and 8 in another disengaged position.

Fig. 10 is a fragmentary detail showing the ratchet driving mechanism for the platen sector, parts being in the position assumed during a printing operation.

Fig. 11 is a similar view showing the parts in one position assumed during repeat printing, and

Fig. 12 is a cross section on line 12—12 of Fig. 10.

Throughout the drawings like reference characters indicate like parts. B is the main frame of the machine adapted to rest upon a table or similar support, and having the horizontal guides G along which stencil cards 33 may be fed in the usual way from magazine X through an inking and impression mechanism to the receiving magazine Y. The mechanism is preferably driven by

a crank 24 having a handle 1 adapted to be grasped by the operator. This crank is rigidly mounted on short shaft 9^a journaled in the main frame, as shown in Figs. 7 and 8, and is clamped thereto by the set screw 24^a. In line with short shaft 9^a and axially movable toward and from it is the ink sector shaft 9. A single jaw clutch 15 is formed by cutting away the abutting ends of shafts 9 and 9^a so that when shaft 9 is forced to the left by spring 13 bearing on collar 14 fast on the shaft, the clutch is in engagement and rotation of the hand crank will also rotate shaft 9 and inking sector 11, and the frictional card feeding sector 31 carried thereby. 12 is a fixed pin set in the main frame engaging a corresponding recess in the inking sector when the latter is forced to the right, (looking at Figs. 7 and 8) so as to disengage clutch 15 as shown in Figs. 8 and 9. To hold the clutch in this disengagement until shaft 9^a is turned far enough to bring the projecting jaws into abutting position, as generally indicated in Fig. 9, I provide a spring 27 mounted on the sleeve 30 surrounding the clutch jaws, and adapted to engage the notch 28 in shaft 9 as shown in Fig. 8. Sleeve 30 is fastened to shaft 9^a by set screw 29 so that spring 27 revolves with the hand crank and is released from notch 28 after the hand crank has made a partial revolution (shaft 9^a being stationary), but by this time the jaws of clutch 15 are in partially abutting position and the clutch is therefore held open until the hand crank has nearly completed a revolution, at which latter time the clutch jaws slip back into engaged position as shown in Fig. 7, by action of spring 13, the spring finger 27 being slid over beyond the notch 28 as there shown before it has an opportunity to engage said notch 28. A spindle 10 extends through a central boring in the shaft 9^a and terminates in a button at its outer projecting end. By pressing on the button the operator can shift shaft 9 into the position shown in Fig. 8 disengaging the clutch and locking the inking sector 11 in raised position, by action of spring finger 27 and pin 12.

On the shaft 9^a is the gear 25 meshing with a similar gear 26 on a third shaft 17 which carries platen sector 16 beneath inking sector 11. This platen sector is loose on shaft 17 but may be rotated in counter-

clockwise direction, looking at Figs. 10 and 11, by the ratchet mechanism there illustrated comprising the pawl 19 pivoted on driving sector 18 and engaging a single tooth 5 19^a on the inner surface of platen sector 16. Driving sector 18 is held fast on shaft 17 by set screw 18^a.

From the foregoing description it is evident that when clutch 15 is in engagement 10 and the hand crank 24 is rotated in clockwise direction as indicated by the arrow in Fig. 1, inking sector 11 and platen sector 16 will rotate in unison, that when clutch 15 is disengaged and inking sector 11 locked by 15 engaging pin 12 and hand crank 24 is rotated in a counter-clockwise direction, neither the inking sector 11 nor the platen sector 16 will rotate, and that when clutch 15 is so disengaged and the hand crank 24 is 20 rotated in clockwise direction, inking sector 11 will alone remain stationary, but platen sector 16 will then rotate idly, having no pressure element with which to cooperate.

Two card feeding mechanisms are employed in this apparatus, one, the usual reciprocating claw feed, not illustrated in detail, for feeding cards out of magazine X into guides G and onward to receiving magazine Y, thus forcing them along through 25 the inking and impression mechanism in regular order for continuous printing or skipping, the other comprising revolving friction sector 31 (best shown in Figs. 7, 8 and 12) which is fast on shaft 9 and projects through a cut away portion of one of 30 the card guides to bear upon the edge of that one of the cards 33 which is in the printing zone, as clearly shown in Fig. 12. This friction feed cooperates with the reciprocating feed to push the card through the printing zone during consecutive printing, is out of action during any skipping operation, and is the only feeding mechanism operated 35 during repeat printing, at which time it moves the card in the printing zone back and forth for the number of printing operations required to be performed therewith.

The reciprocating card feeding mechanism comprises a slide 8, (Figs. 4, 5 and 6) 50 to which the upper end of the feed lever 7 is pivoted, and driving link 6 which is pivoted to lever 7 at a point intermediate of its length and also to the oscillating lever 21 which is loosely mounted on the shaft of bell crank 3—3^a and connected at its other 55 end by link 20 to platen sector 16. Links 4 and 4^a pivoted together at A, form a knee joint by cooperation of the stop 23 carried by link 4. Link 4^a is pivoted at 4^b on a portion of the main frame B, and the free end of link 4 is pivoted to feed lever 7 at 22. When links 4 and 4^a are held down by 60 gravity in the position shown in Figs. 1, 4 and 5, they hold pin 22 rigidly in a fixed 65 position as a rigid fulcrum for feed lever 7

so that as the inking and platen sectors 11 and 16 rotate, the reciprocating movements of link 20, lever 21 and link 6, will oscillate lever 7 on such rigid fulcrum and cause the usual claw feed to deliver cards from magazine X to guides G. 70

If, however, the knee joint A is broken or collapsed by forcing the linkage upward into the position shown in Fig. 6, any pull on link 6 will merely cause the knee joint to collapse further into the position shown in dotted lines therein, thus transforming pin 22 into a floating fulcrum and transmitting no motion to the feed slide 8. This breaking of the knee joint is effected by the bell 80 crank 3—3^a when the short arm 3^a thereof is forced to the left as shown in Fig. 2, by partial rotation of the trip lever 2 mounted on pivot 32. A stop 2^a is provided for limiting this rotation of the trip lever 2 and so 85 preventing it from going in either direction beyond the positions shown in Figs. 1 and 2.

The trip lever 2 is operated for the purpose of oscillating bell crank 3—3^a by plunger 1^b carried by crank handle 1 (see 90 Figs. 3 and 7). A spring 1^a (Fig. 3) normally holds the plunger in the projected position shown in both figures of drawing so that it will strike trip lever 2, but when the handle is pulled outward, this plunger will 95 then pass over trip lever 2.

Such being the preferred construction of parts, the operation is as follows: With the parts in normal position shown in Fig. 1 the operator grasps the crank handle 1, pulls 100 it outward and rotates it in a clockwise direction to consecutively feed stencil cards along guides G, and inserts the envelope or article on which printing is to be done in the guides between the inking sector 11 and 105 platen sector 16 when the latter are in the position shown in Fig. 4. This will produce consecutive printing, on all articles fed to the machine by the operator, from all of the cards fed from the magazine X. If the operator pulls the handle 1 outward so that plunger 1^b clears trip lever 2, the operation 110 is continuous. If he does not pull the handle out far enough, plunger 1^b will strike lever 2 at the end of each revolution and the handle must then be pulled out before another revolution can be made. 115

If the operator desires to skip a card, after looking at it as it lies in the guides G between the magazine X and the inking and impression mechanism, he pushes in plunger 10 as shown in full lines in Fig. 8, thereby breaking clutch 15 and locking the inking sector in raised position. Thereafter a clockwise rotation of crank 24 will feed that card to the receiving magazine Y without printing from it. At the conclusion of this cycle the clutch 15 goes into engagement and spindle 10 is pushed out into the position shown in Fig. 7. If the next card is 120 125 130

to be skipped spindle 10 must be pushed in again, otherwise consecutive printing is resumed.

If, however, the operator wishes to print repeatedly from the card in the printing zone he first makes a reverse or counter-clockwise revolution of the hand crank so that plunger 1^b strikes trip lever 2 on the other side, forcing it into the position shown in Fig. 2. During this counter revolution the feeding sector 31 feeds the card back along the guides, but no inking operation occurs, as the platen sector 16 is allowed to rest in its lowermost position because the pawl 19 exerts no driving force upon it while rotating in the direction indicated in Fig. 11. This consequently leaves the feed slide 8 at rest and no card is fed forward from the magazine to interfere with the backward movement of the card in the printing zone. When plunger 1^b forces trip lever 2 into the position shown in Fig. 2, as above described, the latter raises arm 3 of the bell crank into the position shown in Fig. 6, the parts passing through the intermediate positions shown in Fig. 5. This breaks the knee joint and, as the end of arm 3 then engages notch 5 in link 4 as there shown, the knee joint is held in this initially broken condition while the operator begins giving the hand crank another clockwise revolution to bring the card back between the inking and platen sectors for a second printing. The knee joint is thus held in this position until the lever 21 begins to swing and pull link 6 and feed lever 7 toward it. The knee joint then further collapses into the dotted line position shown in Fig. 6, and no motion is transmitted to the feed slide 8. Bell-crank 3-3^a is then released from engagement with notch 5 and drops back into normal position shown in Figs. 1 and 4. When the clockwise rotation of the crank for a repeat printing has been completed, the parts are thrown or dropped back into the position shown in Figs. 1 and 4, and ordinary printing or skipping can be resumed or another repeat printing may be performed as above described.

It will be observed that the foregoing apparatus last described disables the reciprocating feed during both the backward and forward revolutions of the hand crank. During the backward revolution the disabling results from the action of the ratchet mechanism 19-19' which leaves platen sector 16 quiescent and so transmits no motion to link 20. During the succeeding forward rotation no motion is transmitted to the slide 8 because the knee joint A has been broken and the motion then transmitted to link 20 results only in idly oscillating lever 7 upon its upper pivot.

While I have illustrated and described my invention as applied to a printing appa-

ratus employing stencil cards as an element, it is evident that it could be easily modified to operate with other forms of address bearing strips without departing from the principle of the invention or requiring other than slight changes in the instrumentalities embodying the principles of operation above set forth.

The inking sector 11 may be faced with an absorbent material adapted to receive and retain a large supply of ink, such as described in Patents No. 1,208,268 and No. 1,208,270 granted Edwin D. Belknap December 12th, 1916, or the ink may be continuously supplied to it by any one of many well-known forms of inking device.

Having described my invention I claim:

1. In an addressing machine having stencil card guides, a reciprocating member for feeding said cards into said guides, revoluble inking and platen sectors between which said cards are fed along said guides, and a crank mechanism for rotating said sectors, the combination, with said above described apparatus, of a lever connected to said reciprocating member at one end and to the crank mechanism at a point intermediate of its ends, a movable fulcrum at the other end of said lever, and means adapted to hold said fulcrum rigidly when the cards are to be fed along said guides, but to temporarily release it when the feeding action is to be interrupted.

2. A combination such as defined in claim 1 in which said last mentioned means comprises a knee joint mechanism consisting of two pivotally connected links, one of which is pivoted to said lever and the other to a fixed pin, and intermittently acting mechanism for temporarily forcing said links out of line one with the other, thereby breaking said knee joint.

3. A mechanism for disabling a reciprocating card feeding claw, which mechanism comprises, in combination, a lever pivoted at one of its ends to said claw, a normally stiff knee joint system of links extending from a fixed pivot and connected to said lever at a second point therein, means for continuously oscillating said lever connected to it at a third point therein, and a device for collapsing said knee joint when it is desired to interrupt card feeding.

4. A combination such as defined in claim 3 in which said means for oscillating said lever comprises a hand crank and connections therefrom to said lever, and in which said device for collapsing said knee joint comprises a swinging member, adapted to throw said knee-joint mechanism out of line, and an adjustable projecting element on said crank adapted to vibrate said swinging member when said element is held in proper position during rotation of said crank.

5. A combination such as defined in claim 1

3 in which said means for oscillating said lever comprises a hand crank and connections therefrom to said lever, and in which said device for collapsing said knee joint comprises a bell crank, one arm of which is adapted to strike the knee joint, a finger mounted on a fixed pivot engaging the other arm of said bell crank, and an adjustable plunger in said hand crank adapted to strike said finger when projecting from the crank a certain distance, but to pass over it when withdrawn toward the crank.

6. In a hand operated addressing machine the combination of a reciprocating card feeding mechanism, a lever pivoted at one end thereto, a hand crank, an operative connection from said crank to said lever, two links pivoted together, to a fixed support and to said lever, means for holding said links substantially in line one with another, whereby they then form a rigid fulcrum for said lever, and a trip device optionally operable through the agency of said crank for forcing said links out of line and temporarily holding them in that position, whereby they become free to swing on their connecting pivot and no longer form a rigid fulcrum for said lever.

7. A combination such as defined in claim 6 in which said trip device comprises a bell crank, one arm of which is adapted to engage a notch in the adjacent link when the same has been swung slightly out of line with the other link by said bell crank and thereby constitute said temporary holding means.

8. In an addressing machine the combination of a printing mechanism comprising a revoluble inking sector, a revoluble platen sector, a ratchet mechanism for rotating the platen in one direction, a reciprocating device for feeding stencil cards forward to said printing mechanism operatively connected to said platen sector, a hand crank for rotating said inking sector and one element of said ratchet mechanism, and means under control of the operator for disabling said feeding device during any one forward feeding rotation of said inking sector and ratchet mechanism; whereby repeated printing from any one card is made possible by disabling said reciprocating feeding device during successive backward and forward rotations of said crank.

9. A mechanism such as defined in claim 8 combined with card guides leading from said reciprocating device to said printing mechanism and a feeding sector on said inking platen adapted to frictionally engage the card in said guides and in the printing zone; whereby said card is reciprocated back and forth through said printing zone while said first mentioned reciprocating feed device is left at rest so that no additional cards are fed forward by it.

10. In an addressing machine having an inking mechanism comprising a revoluble inking sector and a revoluble platen sector cooperating therewith, a series of stencil cards, apparatus for feeding said stencil cards to said inking mechanism, and a device for simultaneously operating said elements, the combination with the above recited mechanism of means under control of the operator for disconnecting said inking sector from said actuating device while it is out of inking position; whereby cards may then be fed through without printing or smudging although the other sector is revolving idly.

11. In an addressing machine the combination of a revoluble platen sector, a hand crank operatively connected thereto fixed on a revoluble shaft, a revoluble inking sector fixed on a shaft in line with and movable axially toward and from said crank shaft, a clutch normally connecting said shafts, means under control of the operator for moving said inking sector shaft away from said crank shaft to disconnect said clutch, and a card feeding device having an independent connection to said hand crank, whereby cards may be fed through said inking mechanism while it is disabled by the disconnection of said inking sector from said hand crank.

12. A structure such as defined in claim 11 combined with means for positively holding said inking sector stationary comprising a fixed pin adapted to engage said sector when the latter is forced away from said crank shaft.

13. A structure such as defined in claim 11 combined with means for holding said clutch out of engagement until nearly a complete revolution of said hand crank is effected, but permitting it to reengage at the completion of each revolution.

14. An addressing apparatus comprising, in combination, a series of address bearing stencil cards, an inking mechanism comprising a revoluble inking sector and a revoluble platen sector, guides leading to said printing mechanism, a reciprocating mechanism for feeding said cards along said guides part way into the printing zone, a feed sector revolving with said inking sector and adapted to bear on each card presented for cooperation with the inking mechanism and to feed it through the printing zone, a hand crank, and means under control of the operator for connecting it with some or all of said inking and card feeding elements; whereby all of the cards may be used, or some may be skipped, or repeated printing may be made with any one card.

ERWIN A. GEIGER.
